SAFETY CONTROL FOR WATER-COOLED
REFRIGERATIVE SYSTEMSJohn M. Andrews, York, Pa., assignor to York
Corporation, York, Pa., a corporation of Dela-
ware

Application September 13, 1951, Serial No. 246,381

4 Claims. (Cl. 62—4)

1

This invention relates to refrigeration systems using a liquid cooled condenser, and provides a simple and satisfactorily sensitive means for controlling the rate of cooling liquid supply, and for shutting down the system upon failure of liquid supply. In the ensuing discussion the cooling liquid will be assumed to be water, as is the usual practice.

According to the invention, hot gas entering the condenser from the compressor is directed against a water tube through which cooling water leaves the condenser. The thermal bulb which regulates the rate of cooling-water flow is subject to the temperature of water so heated and preferably is located in the tube.

The supply of motive energy to the compressor is subject on an on-and-off basis to the combined effect of the temperature of the water and the temperature of hot gas entering the condenser.

In this way sufficiently rapid response is assured using a mechanism which is simpler and less expensive than those heretofore considered necessary.

A typical embodiment of the invention will be described by reference to the accompanying drawing in which the single figure is a diagrammatic elevation (with parts broken away) of a refrigerative circuit embodying the invention.

In the drawing the numeral 1 indicates the shell of a water cooled condenser which is cooled by internal water coils to be described. Refrigerant condensed in shell 1 passes by liquid line 2 to a controlling device 3, which may be an expansion valve or the equivalent. This delivers liquid refrigerant at appropriate rates to the evaporator 4 of any suitable type.

The suction line 5 leads from the evaporator 4 to motor driven compressor 6 which compresses refrigerant evaporated in evaporator 4 and delivers it through the "hot gas" line 7 to the condenser shell 1. The device 8 is a relief valve which in response to excessive pressure vents line 7 to line 5. This is commonly required by the underwriters in water cooled systems.

The circuit above described is simply a typical compressor-condenser-evaporator unit which may conform to any accepted practice, and for which no novelty is here claimed. It is typical of the environment in which the invention offers its characteristic advantages.

Outside shell 1 are two water manifolds, a supply manifold 9 and a discharge manifold 11 connected by a plurality of water tubes 12 which extend in parallel through the shell 1. Water is

supplied from city mains through pipe 13 and water regulator valve 20 to supply manifold 9. Thence it passes through tubes 12 to manifold 11, and exchanges heat with the compressed refrigerant vapor in shell 1. Manifold 11 discharges to any point of use of warm water or to waste as circumstances dictate.

According to the invention, hot gas line 7 discharges into shell 1 through a tube 14 which has nozzle ports 15 directed toward one of the tubes 12 near the water exit end thereof. Thus jets of hot gas impinge directly on this tube which is the uppermost tube in the drawing. Thus the hottest vapor exchanges heat with the warmest water with the result that any water failure results in a sharp temperature rise.

In the prior art it has been proposed to subject a thermostatic bulb containing a volatile liquid to the condenser cooling water, and use the resulting vapor pressure to open a water regulating valve more and more in response to rising temperature. Valve 20 is biased to close, but is urged in its opening direction by pressure in tube 16 which leads from thermostatic bulb 17. Valve 20 is open whenever the compressor is operating, but may close if the compressor remains idle for extended periods. Thus a saving in the amount of water used is effected. According to the invention, bulb 17 is located within a tube 12 adjacent the area of hot gas impingement. The thermostatic water valve is known. The novel feature is the location of bulb 17.

A thermostatic switch 18 is mounted on a copper plate 19 brazed to tube 14 (but outside shell 1) and also to that tube 12 in which bulb 17 is located. Switch 18 controls the motor of motor-driven compressor 6 either directly or through any suitable relay switches (not shown). Switch 18 is conventional, but is preferably of the type which will open to stop the compressor when a predetermined maximum temperature is attained and will start the compressor when the apparatus has cooled to a somewhat lower temperature. The difference between these control temperatures is such that "short cycling" of the unit is prevented.

As a consequence the thermostat of switch 18 is affected by the hottest vapor and the warmest water cumulatively so that overloads and water failures each become effective to stop the motor. Any good heat conductor could be used for plate 19, copper being probably the best low cost material available.

The construction is simple and independent of condenser pressure as such. Hence leakage from

the refrigerative circuit is not a problem. The switch 18 or equivalent device is external to the refrigerative circuit and always accessible. Response is much more rapid than can be had with prior art locations of the thermostatic devices. Finally, the scheme meets the underwriters' specifications without involving undue complication and expense.

The illustrated embodiment is, of course, exemplary and subject to modification within the scope of the claims.

What is claimed is:

1. In a refrigerative circuit of the compressor-condenser-evaporator circuit type having a water-cooled surface condenser, and a thermostatically controlled regulating valve for varying the flow of cooling water through said condenser, the improvement which comprises means for directing at least a major portion of the hot gas entering the condenser against a minor portion of the water-cooled heat exchange surface of the condenser close to the point of cooling water exit whereby a portion of the cooling water is intensively heated, the thermostatic element of said valve being located in the cooling water near said minor portion of the heat exchange surface whereby it is subject principally to heat exchange with the water so heated intensively.

2. A refrigerative circuit comprising a motor-driven compressor; a water-cooled surface condenser; an evaporator; water connections through which cooling water passes to and from said condenser; refrigerant connection completing the circuit and including a hot gas line which leads from the compressor to the interior of the condenser and there discharges against a minor portion of the water-cooled surface close to an exit connection for cooling water to afford localized intense heating of a portion of the exit water; and a thermostatic controller for the motor which drives the compressor, said controller being subject at least in part to the temperature of water so heated intensively.

3. A refrigerative circuit comprising a motor-driven compressor; a water-cooled surface condenser; an evaporator; water connections through which cooling water passes to and from

said condenser; refrigerant connections completing the circuit and including a hot gas line which leads from the compressor to the interior of the condenser and there discharges against a minor portion of the water-cooled surface close to an exit connection for cooling water to afford localized intense heating of a portion of the exit water; and a thermostatic controller for the motor which drives the compressor, said controller being subject to the combined effect of the temperature of the hot gas entering the condenser and the temperature of the water so heated intensively.

4. A refrigerative circuit comprising a motor-driven compressor; a water-cooled surface condenser; an evaporator; water connections through which cooling water passes to and from said condenser; refrigerant connections completing the circuit and including a hot gas line which leads from the compressor to the interior of the condenser and there discharges against a minor portion of the water-cooled surface close to an exit connection for cooling water to afford localized intense heating of a portion of the exit water; a thermostatic controller for the motor which drives the compressor, said controller being subject to the combined effect of the temperature of the hot gas entering the condenser and the temperature of the water so heated intensively; and a thermostatically controlled regulatory valve interposed in said water connections to vary the flow of cooling water and subject to the temperature of exit water substantially at the point of said intense heating.
